US00D983557S

(12) **United States Design Patent** (10) Patent No.: **US D983,557 S**
(45) Date of Patent: **** Apr. 18, 2023**

(54) **PAPER DISPENSER**

(71) Applicant: **CASCADES CANADA ULC**, Kingsey Falls (CA)

(72) Inventors: **Benoit Orban**, Saint-Lambert (CA); **Méloidy Sue Myette**, Montréal (CA)

(73) Assignee: **CASCADES CANADA ULC**, Kingsey Falls (CA)

(**) Term: **15 Years**

(21) Appl. No.: **29/777,648**

(22) Filed: **Apr. 7, 2021**

Related U.S. Application Data

(62) Division of application No. 29/659,946, filed on Aug. 14, 2018, now Pat. No. Des. 918,615.

(57) **CLAIM**

The ornamental design for a paper dispenser, as shown and described.

DESCRIPTION

FIG. 1 is a perspective view of a paper dispenser; FIG. 2 is a front elevation view of the paper dispenser shown in FIG. 1;

FIG. 3 is a rear elevation view of the paper dispenser shown in FIG. 1;

FIG. 4 is left-side elevation view of the paper dispenser shown in FIG. 1;

FIG. 5 is right-side elevation view of the paper dispenser shown in FIG. 1;

FIG. 6 is a top plan view of the paper dispenser shown in FIG. 1; and,

FIG. 7 is a bottom plan view of the paper dispenser shown in FIG. 1.

The broken lines shown in the figures represent portions of the paper dispenser that form no part of the claimed design.

1 Claim, 7 Drawing Sheets
